UNITED STATES PATENT OFFICE.

WILLIAM C. GREGG, OF SUMMERTON, SOUTH CAROLINA.

PROPELLER FOR SHIPS.

1,306,892.

Specification of Letters Patent. Patented June 17, 1919.

Application filed March 30, 1918. Serial No. 225,775.

To all whom it may concern:

Be it known that I, WILLIAM C. GREGG, a citizen of the United States, residing at Summerton, in the county of Dorchester 5 and State of South Carolina, have invented certain new and useful Improvements in Propellers for Ships, of which the following is a specification.

This invention relates to propellers for ships, and more particularly to propellers of the reciprocating type.

The objects of the invention are to provide an improved mechanism of this character which shall be simple and rugged in construction and more efficient in operation than propellers heretofore proposed. Other objects will appear from the following description.

In order that the invention may be clearly understood, reference is had to the accompanying drawings, forming part of this specification, and in which,

Figure 1 is a plan view, partly in section, showing the stern of a vessel equipped with my improved propeller;

Fig. 2 is a plan view of the duplex steam engine with cross-connected valves which I preferably employ for actuating my improved twin propellers, parts being broken away;

Fig. 3 is a side elevation thereof;

Fig. 4 is a front elevation of one of my improved propellers, the same being shown in its open or operative position;

Fig. 5 is a rear view thereof;

Fig. 6 is a view similar to Fig. 5, showing the propeller in its partially collapsed position; and,

Fig. 7 is a diagrammatic view in side elevation showing the bow of a ship equipped with a backing propeller, and also illustrating a slightly modified construction of propeller.

Referring to the drawings in detail, the hull of the ship is indicated by the letter S, and the usual rudder by R. My improved twin propellers are arranged one on each side of the rudder, and are designated by the letters A and B. The propeller A is connected by means of a piston rod *a* with a steam cylinder A', and the propeller B is connected by means of a piston rod *b* with a steam cylinder B'.

As the detailed mechanical construction of each propeller and associated parts is identical, a description of one will suffice for both.

Referring to the drawings, and more particularly to Figs. 1, 4, 5, and 6 thereof, my improved propeller comprises in general a hollow pyramid or cone-shaped shell, shown 60 as octagonal, made up of a series of wings or sections 1, pivotally connected to interposed ribs 2. As clearly shown in Figs. 4 and 5, the sections are united to the ribs by means of hinges 3 and 4 at their edges, the 65 said hinges 3 and 4 being disposed alternately outside and inside of the propeller, respectively. By virtue of this construction, it will be obvious that the propeller is capable of folding or collapsing, as shown in 70 Fig. 6, alternate ribs moving inwardly toward the axis of the cone. The ribs and sections are provided at their forward ends with suitable trunnions 5, rotatably mounted in a cone-shaped head 6, having rearwardly 75 projecting portions 6^a, serving as stops against which the ribs and sections engage when the propeller is in its open position, as shown at A, in Fig. 1.

The head 6 is rigidly secured to the outer 80 end of a piston rod consisting of a hollow tube 7, extending through a suitable stuffing box 8, mounted in the side of the ship. The inner end of the rod 7 enters a steam cylinder 9 and is connected with a piston 10, 85 freely movable in said cylinder. As shown in Fig. 1, this piston preferably consists of a pair of spaced guide members 10^a and 10^b, connected by a suitable yoke. A pair of auxiliary pistons 11 and 12 are also arranged 90 in the cylinder 9, one on each side of the piston 10, and are provided with the usual packing rings, not shown, to secure a steam-tight fit. The pistons 11 and 12 are spaced apart a distance slightly greater than the 95 length of the piston 10, and are maintained in such spaced relation by means of a rod 13, passing freely through the piston 10. The piston 12 is slidably mounted on the tube 7. The rod 13 is pivotally connected 100 to one end of a lever 14, pivotally mounted in the yoke of the piston 10, the other end of which is connected by means of a link 15 with one end of a rod 16. This rod 16 extends throughout the length of the tube 7 105 and, after passing through a suitable stuffing box 17, at the outer end of such tube, projects into the interior of the propeller. Secured to the outer end of the rod 16 is a block 18, and extending radially from such 110 block is a plurality of arms or braces 20, pivotally connected at one end to the block

18, as indicated at 19, and at the other end to the ribs 2, as indicated at 21. It will be noted that there are eight ribs shown in the drawings and that four of the arms or 5 braces 20 are provided, such braces being connected to the alternate ribs, as clearly shown in Fig. 5.

As a result of the construction above described, it will be obvious that a forward 10 movement of the rod 16 results in forcing the ribs 2 outwardly and thus expanding the propeller, as shown at A in Fig. 1, while a rearward movement of the rod results in drawing the alternate ribs inwardly and 15 collapsing the propeller, as shown in Fig. 6, or at B, in Fig. 1. It will be further understood that when steam is admitted to either end of the cylinder 9, as hereinafter described, the first effect is to produce an 20 initial movement of the connected auxiliary pistons 11 and 12, in one direction or the other, as the case may be, which movement, by means of the connections 14 and 15, above described, results in the shifting of the rod 25 16 and the consequent expanding or collapsing of the propeller. It will thus be seen that I have provided positive mechanical means for expanding the propeller at the beginning of its outward stroke and for 30 collapsing the propeller prior to the beginning of the inward or return stroke.

In order to produce the proper alternate reciprocations of the propellers A and B without the use of gearing or other complicated mechanism, I prefer to employ the arrangement of steam engine cylinders and valves shown in the drawings. In such arrangement, I have so designed the valve gear that the valves of cylinder A' are controlled by the movements of propeller B, while the valves of cylinder B' are controlled by the movements of propeller A. 40

To this end, I mount on each piston rod 7, a suitable arm or bracket 22, carrying a 45 pin 23, working loosely in a slot 24, formed in a valve actuating rod 25, slidably supported adjacent each cylinder. The ends of the rods 25 are connected to cranks 26, secured to a pair of cross rock shafts 27, 50 extending between the two cylinders. Each rock shaft 27 carries at its end opposite to the crank 26, a crank 28, which crank is connected with a valve rod 29, having an operative connection with a pair of oscillatory valves 30, preferably of the Corliss type. These valves control both the inlet 55 to and exhaust from the cylinders in a well known manner.

Steam is supplied through the main X, 60 having the branch connections 31, 32, 33, and 34, leading to the four valves, while the exhaust escapes from the main Y, communicating with the branch pipes 35, 36, 37, 38, and 39, extending from the valves. 65

From the above, it will be seen that at

the end of the stroke of piston rod b, for example, the pin and slot connection 23 and 24, acting through the elements 25, 26, 27, 28, and 29, the valves 30 of cylinder A' are operated, and vice versa. It is clear that 70 suitable lugs or tappets may be substituted for the pin and slot connection shown, as in engines of well known types. It will also be understood that in practice the cylinders A' and B' will be much longer in 75 proportion than shown in the drawings, so as to give a long stroke to the propellers. It is quite possible that in the larger ships, the propellers will have a stroke of from ten to fifteen feet, or more. Where pistons 80 with such long strokes are employed, it will probably be preferable to have the valve operating rods 25 extend through independent stuffing boxes in the hull, the brackets such as 22 being fixed at the rear ends of 85 the piston rods, near the propellers. This will enable the cylinders to be placed close up in the stern where they occupy substantially the same space as is now occupied by the turbines in twin screw steamers. 90

In order to reverse the direction of the ship or vessel, I propose to mount in the bow a single propeller C, similar to the propellers A and B, as shown in Fig. 7. This propeller will be actuated through a 95 piston rod c, by means of a single cylinder reciprocating engine, the valves of this engine being actuated at the end of the stroke of the piston by means of tappets, as is common in pumping engines. It is thought 100 this construction will be obvious without further detailed description or illustration.

In certain classes of vessels, such, for example, as battle ships, it will be desirable to utilize the reciprocating bow propeller 105 as a weapon of attack. To such end, I propose to extend the piston rod through the propeller and provide the projecting end with a point of hardened steel, or the like, to constitute a ram 40, as shown in Fig. 7. 110

It will be understood that the backing propeller and ram shown in Fig. 7 will normally be housed in a compartment at the bow separated from the rest of the ship by means of suitable bulk heads, as indicated in dotted lines. This is for the purpose of obviating water resistance when the ship is moving forward. The propeller will be projected into full line position only 115 when being used. The compartment may 120 be provided with a movable door, as shown, if desired.

What I claim is:

1. A reciprocatory propeller comprising a cone-shaped shell made up of a plurality 125 of sections and interposed ribs to which said sections are pivotally connected.

2. A reciprocatory propeller comprising a cone-shaped shell made up of sections and interposed ribs to which said sections are 130

pivots connected, and means for moving said ribs to collapse the propeller.

3. A propeller comprising a shell made up of pivots connected ribs and sections, 5 means for reciprocating said propeller, and mechanical positively acting means connected to said ribs for expanding and collapsing said shell prior to the beginning of each stroke of the propeller.

10 4. A propeller comprising pivots connected sections, a hollow piston rod to which said propeller is secured, a steam cylinder having a piston rigidly mounted on said piston rod, an actuating rod extending 15 through said hollow piston rod and connected with said sections, and means operating upon the admission of steam to said cylinder to first shift said actuating rod to expand or collapse said propeller sections 20 and then bodily move the piston rod and propeller.

5. A propeller comprising pivots connected sections, a hollow piston rod to which said propeller is secured, a steam cylinder 25 having a piston attached to said piston rod, an actuating rod extending through said hollow piston rod and connected with said sections, a pair of auxiliary pistons in said cylinder spaced apart and disposed one on 30 either side of said first named piston, said auxiliary pistons being operatively connected with said actuating rod, whereby,

when steam is admitted to said cylinder, said auxiliary pistons are first moved to shift said actuating rod to expand or collapse said propeller, and then the piston rod 35 and propeller are bodily moved.

6. A propeller comprising a cone-shaped shell made up of a plurality of sections with ribs disposed between the edges thereof and 40 pivoted thereto, means for reciprocating said propeller, and an actuating rod connected with alternate ones of said ribs and serving to positively expand or collapse said shell prior to each stroke of said propeller. 45

7. A pair of reciprocating propellers, a separate steam cylinder for actuating each, and means for causing one propeller to begin its stroke at the end of the stroke of the other, whereby said propellers operate alternately. 50

8. A pair of reciprocating propellers, a separate steam cylinder for actuating each, inlet and exhaust valves for each cylinder, and means for operating said valves, the 55 operating means for the valves of one cylinder being connected with and actuated by the propeller driven by the other cylinder.

In testimony whereof I affix my signature in presence of two witnesses.

WILLIAM C. GREGG.
